Sidney Rubeck, New York, N. Y.

Application June 11, 1954, Serial No. 30,932

Term of patent 7 years

(Cl. D48—20)

To all whom it may concern:

Be it known that I, Sidney Rubeck, a citizen of the United States of America, residing in New York city, county of New York, and State of New York, have invented a new, original, and ornamental Design for a Lamp or Similar Article, of which the following is a specification, reference being had to the accompanying drawing, forming part thereof.

Fig. 1 is a front elevational view of a lamp or similar article showing my new design.

Fig. 2 is a side elevational view thereof.

The dominant feature of my design resides in the portions shown in solid lines.

I claim:

The ornamental design for a lamp or similar article, substantially as shown and described.
